UNITED STATES PATENT OFFICE.

ROBERT MCMAHON, OF NEW YORK, N. Y.

PAPER-FASTENER.

SPECIFICATION forming part of Letters Patent No. 693,302, dated February 11, 1902.

Application filed August 21, 1901. Serial No. 72,757. (No model.)

To all whom it may concern:

Be it known that I, ROBERT MCMAHON, a citizen of the United States, and a resident of the city of New York, borough of Manhattan, 5 in the county and State of New York, have invented a new and Improved Paper-Fastener, of which the following is a full, clear, and exact description.

The object of the invention is to provide a 10 new and improved paper-fastener which is simple and durable in construction, easily applied to fasten a desired number of superimposed sheets securely together, and to provide an eyelet for the passage of a seal-ribbon 15 for sealing the papers.

The invention consists of novel features and parts and combinations of the same, as will be fully described hereinafter and then pointed out in the claims.

20 A practical embodiment of the invention is represented in the accompanying drawings, forming a part of this specification, in which similar characters of reference indicate corresponding parts in all the views.

25 Figure 1 is a rear face view of superimposed sheets with the front member of the fastener shown in dotted lines in position. Fig. 2 is a rear face view of the sheets with both members of the fastener in position. Fig. 3 is a like 30 view of the same with the parts in a different position. Fig. 4 is a like view of the same with the members of the fastener securely locked together. Fig. 5 is an enlarged sectional elevation of the improvement on the 35 line 5 5 of Fig. 2, and Fig. 6 is a perspective view of the front member.

35 The improved paper-fastener consists, essentially, of the members A and B, made of sheet metal or other suitable material, and between which the superimposed sheets C are held and fastened together, as hereinafter more fully explained. The member A is preferably used on the front face of the superimposed sheets, and is hence the front member, 45 while the other member is applied to the back of the superimposed sheets. The front member A is provided at diagonal corners with pins D, adapted to pass through the superimposed sheets C and through registering apertures E, formed in the rear member B, as

plainly indicated in Fig. 5. The pins D are bent onto the outer face of the back member B, the bent-over portions of the pins extending longitudinally parallel to each other, as plainly indicated in Fig. 3, and in order to 55 conceal the pins and to lock the same in place flaps B', extending integrally from the rear member B, are bent over onto the said pins, as plainly indicated in Fig. 4. The front member A is provided at or near its middle with 60 an aperture A', registering with a similar aperture B², formed in the rear member B, and the side edges of the flaps B' are formed with cut-out portions B⁴, so that when the flaps are folded over the pins, as previously explained, 65 then the said flaps do not cover up the aperture B², as the cut-out portions B⁴ register with the aperture. Thus a seal-ribbon may be readily passed through the fastener whenever it is desired to seal the papers, it being 70 understood that the paper material of the sheets E extending in the apertures can either be punched out previous to applying the fastener or it may be readily cut out by a knife or other suitable tool after the fastener is applied. In order to prevent the pins D from being accidentally bent over the apertures B², I prefer to form on the outer face of the rear member B an annular boss or projection B³, 75 surrounding the aperture B² and forming a 80 guard for the pins D. The boss B³ is of about the same height as the thickness of the pins D, so that when the flaps B' are folded upon the pins the boss does not project beyond the outer faces of the flaps. 85

In using the device the front member A is pressed against the superimposed sheets C, so as to cause the pins D to penetrate the sheets, and then the rear member B is engaged with the pins on the back of the sheets, after which 90 the pins are bent over, as described. Then the flaps B' are folded upon the pins to conceal and lock the same. The papers are now securely clamped between the members A and B. 95

The device is very simple and durable in construction, can be very cheaply manufactured and readily applied, and whenever it is desired to disconnect the superimposed sheets the user can readily bend the flaps B' 100

back to their original position and then bend the pins back and separate the members A and B from each other.

As the pins D are completely concealed, it is evident that they cannot catch on other papers or other articles with which they come in contact.

Having thus described my invention, I claim as new and desire to secure by Letters

10 Patent—

1. A paper-fastener comprising two members, of which one is provided with pins for passing through the papers and for engaging the other member, the said members having 15 registering apertures for the passage of a seal-ribbon, and flaps on the other member for concealing and locking the pins without covering the registering apertures, as set forth.

2. A paper-fastener, comprising a front 20 member having a plurality of pins, a rear member having apertures for the passage of the pins, and flaps extending integrally from the said rear member for folding over the pins to conceal and lock the pins in place, the rear 25 member having a boss for guiding the pins into a bent position, as set forth.

3. A fastener comprising a member provided with pins and with a ribbon-receiving aperture, and another member provided with 30 perforations arranged similarly to the pins on the first-named member and also provided with a ribbon-receiving opening, whereby the members may be assembled for the pins to

pass through the perforated member and the ribbon-openings of the two members are 35 brought into registering relation.

4. A fastener comprising two members each having a ribbon-aperture, and means for positively locking or uniting said members together, whereby the apertures in said members may be brought into registration and adapted to receive a fastening-ribbon. 40

5. A fastener comprising a member having pins and a ribbon-opening, another member provided with apertures and with a ribbon-opening, and bendable flaps projecting from the last-named member and having notches arranged, in the bent positions of the flaps, to lie coincident with the ribbon-opening in the member. 45

6. A fastener comprising a member having pins projecting from diagonal corners thereof, and also having a ribbon-aperture, another member provided with pin-apertures and with a ribbon-aperture, and flaps on the last-named member adapted to be individually bent into locking engagement with the ends of said pins when the latter are bent onto the last-named member. 50

In testimony whereof I have signed my 60 name to this specification in the presence of two witnesses.

ROBERT MCMAION.
